UNITED STATES PATENT OFFICE.

JOHN F. O'CONNOR, OF CHICAGO, ILLINOIS, ASSIGNEE TO WILLIAM H. MINER, OF CHICAGO, ILLINOIS.

DRAFT-RIGGING FOR RAILWAY-CARS.

1,136,037.

Specification of Letters Patent. Patented Apr. 20, 1915.

Application filed March 20, 1913, Serial No. 755,830. Renewed August 12, 1914. Serial No. 856,492.

To all whom it may concern:

Be it known that I, JOHN F. O'CONNOR, a citizen of the United States, residing at Chicago, in the county of Cook and State of Illinois, have invented a certain new and useful Improvement in Draft-Rigging for Railway-Cars, of which the following is a full, clear, concise, and exact description, reference being had to the accompanying drawings, forming a part of this specification.

My invention relates to improvements in draft rigging for railway cars.

In those types of draft rigging employing stop members secured to draft members and a draft gear mounted between followers, which followers are adapted to engage the said stop members, the common practice in applying the draft gear, followers, yoke and draw bar to the car in first assembling these parts, or in replacing or changing these parts, is to place the followers and the draft gear within the yoke, and then to lift the parts so assembled from underneath the draft members into position between the same, engaging the followers with the stop members, and then to apply the means, such as a tie plate, upholding the said parts of the draft rigging in their position between the draft members.

The object of my invention is to provide a means of easily assembling these parts between the draft members so that inaccuracies in the position of the parts within the draft yoke in their assembled relation before the same are placed between the draft members, or inaccuracies in exact dimensions of the parts will not hinder in the ready and quick mounting of the draft gear, yoke and followers between the draft members. The practice heretofore has been to provide stop members having stop shoulders at right angles to the draft member.

I accomplish the object of my invention by providing followers having faces adapted to engage with the ends of the draft gear, but provided at their edges with angular faces.

I provide the stop shoulders of the stop members with similar angular faces so that either the shoulders of the stop members on one draft member converge upwardly toward each other with the edges of the followers adapted to engage with said shoul-

ders similarly converging. In the form of my invention illustrated in the drawings I have depicted stop members in which the stop shoulders on the same draft member converge upwardly toward each other, and the edges of the followers adapted to engage the same are similarly converged. It will be understood however, that by illustrating and describing this one form of my invention I do not intend to be limited only to the specific construction hereinafter detailed.

In the drawings forming a part of this specification Figure 1 is an elevation of a stop member in its position upon a draft member. Fig. 2 is a plan view of a draft rigging illustrating with other parts the stop members and followers embodying my invention. Fig. 3 is a perspective view of one of the followers. Fig. 4 is a perspective view of a modified form of follower.

Referring to the drawings 5, 5 represent draft members or parts of the car frame to which the draft rigging is applied, 6, 6 stop members, 7 the draw bar partially shown in the drawings, 8 the draft yoke partially shown in the drawings, 9 the draft gear, 10 the tie plate, 11 the front follower, and 12 the rear follower. Each stop member 6 may be in the form of a cheek plate illustrated in Fig. 1 of the drawings, having a plurality of stop shoulders, or may consist of a plurality of stop members secured to either draft member.

In the form of stop members illustrated in the drawings each stop member comprises a cheek plate 13 suitably secured, preferably by the rivets 14, 14, to draft member. It will be understood that there is one cheek plate secured to the inner face of each draft member, and that the same are oppositely arranged. One is the counterpart of the other, and I will therefore describe one of the cheek plates. The same is provided with a front stop shoulder 16, the said stop shoulder extending outwardly from the draft member, and from its bottom end 17 to its upper end 18 the same angles rearwardly, as illustrated in Fig. 1 of the drawings. The cheek plate 13 is also provided with a front limiting stop shoulder 19, which from its bottom 20 to its top 21 angles rearwardly, paralleling the front stop shoulder 16. The cheek plate 13 is also provided

with the rear stop shoulder 22 extending outwardly from the draft member, and from its bottom end 23 to its top end 24 angles forwardly, that is, from the bottom toward the top the front stop shoulders and rear stop shoulders converge. The cheek plate 13 is also provided with a rear limiting stop shoulder 25, which from its bottom 26 to its top 27 parallels the rear stop shoulder 22.

10. The front follower 11 comprises a plate substantially rectangular in shape, having a forward face 29 and a rear face 30 substantially parallel to each other, the said faces being at substantially right angles in both vertical and horizontal plane to the central line of the draft gear, the rear face 30 thereof being adapted to engage with the forward end of the draft gear. At either side the said follower is provided with an angular portion 31, the front and rear faces 32 and 33 respectively of said angular portion being oblique to the plane of the faces 29 and 30 of said follower. When the said follower is in normal position and mounted between the stop members the front faces 32, 32 of the angular portion 31 are adapted to engage with the front stop shoulder 16, and on rearward movement of the said follower in buffering movement of the draft gear 30 the rear faces 33, 33 of said angular portion engage the limiting stop shoulder 19, and limit the compressing movement of the gear.

The rear follower may be a duplicate of the front follower. In the modified form of follower illustrated in Fig. 4 of the drawings the same is provided with a forward face 35 adapted to engage the rear end of the draft gear 9, and a rear face 36 substantially parallel to the rear face of the draft gear 9, and provided at either side with an angular portion 37, each rear face 38 of which is oblique to the face 36, the same being adapted to engage the rear stop shoulder 22 when in normal position in relation thereto. 45 In employing the modified form of follower the limiting stop shoulders are at right angles to the length of the cheek plates, and the edges of the followers adapted to engage the limiting stop shoulders are in the same plane as the portion engaging the draft gear.

When in mounting the draft yoke and the followers and draft gear within the yoke into position between the draft members, and in engagement with the stop members, because of the angular portions at the edges of the followers the angular portion on one side of one follower converging from the bottom upwardly toward the angular portion on the same side of the other follower, and because of the converging of the stop shoulders upwardly toward each other the stop shoulders and the angular edges of the followers do not meet until the yoke, followers and draft gear have been lifted into

their position between the draft members. The clearance between the angular edges of the followers and the stop shoulders while the said parts are being lifted into position permits of the ready mounting of said parts, 70 and the easy change of the same when required in the practical operation of railroads.

I claim:

1. In a draft rigging, in combination, stop 75 members and followers, the stop members being provided with stop shoulders converging upwardly toward each other, and the followers being provided with angular members adapted to engage the said stop shoul- 30 ders.

2. In a draft rigging, in combination, draft members, stop members secured there- 85 to, the stop members on each draft member being provided with stop shoulders, said stop shoulders converging upwardly toward each other.

3. In a draft rigging, in combination, stop 90 members and followers, the stop members being each provided with shoulders adapted to engage the followers, the said followers being each provided with marginal edges converging upwardly toward each other.

4. In a draft rigging, in combination, stop 95 members, followers and a draft gear, the fol- 100 lowers being each provided with a face adapted to engage one end of the draft gear, and each having marginal edges whose plane is oblique to the face engaging the draft gear, the said stop members being provided with shoulders adapted to engage the fol- 105 lowers.

5. In a draft rigging, in combination, stop 110 members, front and rear followers and a draft gear, the stop members being each pro- 105 vided with front and rear stop shoulders, said stop shoulders converging upwardly to- 115 ward each other, the followers being each provided with a face adapted to engage an end of the draft gear, and each having a marginal edge at either side thereof, adapt- 110 ed to engage one of the stop shoulders, the said marginal edges of the front follower converging toward the marginal edges of the rear follower.

6. In a draft gear, in combination, draft 120 members, a pair of cheek plates oppositely arranged, and one secured to each draft member, front and rear followers, and a draft gear between said followers, each of 125 said cheek plates being provided with front and rear upwardly converging stop shoul- 125 ders, each of the followers engaging one end of the draft gear, and each having oblique marginal edges adapted to engage the stop shoulders of the cheek plates.

7. In a draft rigging, in combination, stop 130 members, a draft gear and front and rear followers, the stop members being provided with stop shoulders, the front follower being

provided with a face adapted to engage the front end of the draft gear, and marginal edges adapted to engage the front shoulders of the stop members, said marginal edges being oblique to the face of the follower engaging the front end of the draft gear, the rear follower being provided with a face adapted to engage the rear end of the draft gear, and marginal edges adapted to engage the rear shoulders of the stop member, said marginal edges being oblique to the face of the follower engaging the rear end of the draft gear.

8. In a draft rigging, in combination, draft members, stop members, a draft yoke, a draft gear, front and rear followers, the followers and draft gear being adapted to be assembled within the draft yoke, the stop members being provided with upwardly converging stop shoulders, and the followers being each provided with oblique marginal

edges adapted to engage the said stop shoulders.

9. In a draft rigging, in combination, draft members, stop members secured thereto, a draft yoke and a draft gear, and followers within the yoke, the said stop members being provided with upwardly converging stop shoulders, and the followers being provided with similarly upwardly converging marginal edges adapted when the assembled yoke, draft gear and followers are being raised between the draft members to clear the shoulders of the stop members until the followers are raised to normal position between the draft members, whereupon the followers engage the shoulders of the stop members.
